DESIGN FOR A SHOVEL RACK

Arvid P. Zetterberg, New Castle, Ind., assignor to
Borg-Warner Corporation, Chicago, Ill., a cor-
poration of Illinois

Application October 9, 1941, Serial No. 103,696

Term of patent 14 years

To all whom it may concern:

Be it known that I, Arvid P. Zetterberg, a citizen of the United States, residing at New Castle, in the county of Henry and State of Indiana, have invented a new, original, and ornamental Design for a Shovel Rack, of which the following is a specification, reference being had to the accompanying drawing, forming part thereof.

Fig. 1 is a front perspective view of a shovel

rack, showing my new design; Fig. 2 is a rear perspective view thereof on a reduced scale; and Fig. 3 is a side elevational view thereof on a reduced scale.

I claim:

The ornamental design for a shovel rack, as shown.

ARVID P. ZETTERBERG.
